UNITED STATES PATENT OFFICE.

GEORGE H. SHANE AND ROBERT E. FORESMAN, OF DENVER, COLORADO.

RAILWAY-TIE AND CONNECTION.

No. 894,072.

Specification of Letters Patent.

Patented July 21, 1908.

Application filed December 21, 1907. Serial No. 407,534.

To all whom it may concern:

Be it known that we, GEORGE H. SHANE and ROBERT E. FORESMAN, citizens of the United States, and residents of Denver, in the county of Denver and State of Colorado, have invented a new and Improved Railway Tie and Connections, of which the following is a full, clear, and exact description.

This invention has reference to improvements in railway ties and connections, and has in view the provision of a metal tie possessing strength without being unduly heavy and having the requisite amount of elasticity; together with means for assembling the rails 15 with the tie in such a manner that the gage of the track is correctly arrived at in the assemblage of the parts, and will permanently remain.

Reference is to be had to the accompanying drawings forming a part of this specification, in which similar characters of reference indicate corresponding parts in all the views.

Figure 1 is a cross-section through a railway track embodying our invention; Fig. 2 is a plan of the same; Fig. 3 is a fragmentary longitudinal section through the tie at the point of the rail connection; Fig. 4 is a section substantially on the line 4—4 of Fig. 3, looking in the direction of the arrow; and Fig. 5 is a side elevation of a fish-plate as used in connecting the two abutting rail ends with our improved tie.

Our invention includes a channeled metal tie 10, comprising a base-plate provided with upwardly-projecting longitudinal flanges 11 arranged at opposite sides, preferably inset a slight distance from the margin of the base-plate, as clearly shown in Figs. 2 and 4. The flanges 11 are of reduced height at the intermediate portion of the tie, as shown in Fig. 1, and are elevated at the points where the rails are to be connected. These elevated portions of the flanges are each connected by a pair of spaced upwardly-projecting cross-flanges 12, forming a pocket, over which, and extending some distance at each side, is seated a chair 13, made in two sections of like construction; the opposed faces of the sections being suitably shaped for receiving and embracing the flange and web of an ordinary railway rail 14. The sections of the chair are rabbeted on their under faces at their outer ends as indicated at 15, to provide shoulders 16, which abut against the cross-flanges 12 and thus positively prevent

any longitudinal slipping of the chair on the tie, and consequent spreading of the rails.

The longitudinal flanges 11 of the tie at the opposite sides of the pocket are cut out as indicated at 17 in Fig. 2, to an extent equal to 60 the depth of the shoulders 16, in order that the projecting portion on the under face of the chair, resulting from the rabbeting, may extend over the top of these flanges.

The top faces of the chair sections have 65 ribs 18 projecting upwardly from their edges, and the under faces thereof are provided with depending flanges 19, as shown in Fig. 1, for embracing the longitudinal flanges of the tie at opposite sides. Through these 70 flanges pass bolts or other equivalent devices 20, securely connecting the chair and tie together.

In Fig. 5 we have shown in side elevation, 75 a fish-plate which we preferably use in connecting the abutting rail ends, the same embodying the usual angular plate 21 for bearing against the rails' webs, and having bolt-holes 22, the opposite ends of the plate being integral or otherwise rigid with railway chair 80 sections 13^a, of the same construction as the chair sections 13. These fish-plates are assembled with the ties in the same manner as the chairs, the length of the fish-plates obviously determining the distance the ties are 85 spaced apart.

By the especial construction of the tie, it is sufficiently flexible to prevent the undue vibration and jarring of trains, yet strong enough to stand the severest strains to which 90 it is subjected, and by the novel rail fastenings it is impossible for the rails to spread, cant or turn over, but will be held permanently spaced to the proper gage.

The invention as shown and described 95 while being the preferred manner of construction of our improved railway tie and connection, it will be apparent to those skilled in the art that modifications may be resorted to within the scope of the appended 100 claims.

Having thus described our invention, we claim as new and desire to secure by Letters Patent:

1. The combination of a channeled railway tie, and a divided chair seated on the tie over the channel therein and having downwardly-projecting flanges embracing the opposite sides of the tie, both portions of the chair being of like construction a rail seated 105 seated 110

- on the chair and engaged between the portions thereof, and means passing through the flanges of the chair and the tie, connecting them together.
5. 2. The combination of a railway tie, having a transversely cut out portion providing shoulders, a chair made in two sections, each having a shoulder adapted to abut against the shoulder of the tie and provided with depending flanges embracing the opposite sides of the tie, a rail seated within and embraced by the chair, and means passing through said flanges of the chair and tie, connecting them together.
15. 3. The combination of a railway tie, having upwardly-projecting longitudinal flanges at opposite sides and provided with transverse upwardly-projecting flanges near each end, forming in connection with the longitudinal flanges a pocket, a chair seated over the pocket having shoulders abutting against the transverse flanges, and provided with depending flanges at the outside of the longitudinal flanges of the tie, and means connecting the longitudinal flanges of the tie and the depending flanges of the pocket together.
4. The combination of a railway tie, having upwardly-projecting longitudinal flanges at opposite sides, and having means extending from the inner faces of said flanges near each end of the tie, providing shoulders spaced apart, a chair made in two sections, each having a shoulder on its under face

adapted to abut against the shoulders near one end of the tie, and provided with depending flanges embracing the longitudinal flanges of the tie at opposite sides, and means passing through the depending flanges of the chair and the longitudinal flanges of the tie, connecting the chair and tie together.

5. The combination of a railway tie, having longitudinal upwardly-projecting flanges arranged at opposite sides, shoulders spaced apart extending from the inner faces of the flanges near each end of the tie and forming pockets, and a sectional chair having shoulders on its under face adapted to abut against the first mentioned shoulders when the chair is seated on the tie over the pocket.

6. The combination of a railway tie, having longitudinal upwardly-projecting flanges and having spaced transverse flanges near each end, and a chair composed of two like sections, each being rabbeted on the under face thereof to provide a shoulder, the shoulders being adapted to abut against the transverse flanges when the chair is seated on the tie.

In testimony whereof we have signed our names to this specification in the presence of two subscribing witnesses.

GEORGE H. SHANE.
ROBERT E. FORESMAN.
